COMPARTMENTED PACKAGING TRAY

Carlo Caprioli, Montreal, Quebec, Canada, assignor to
Plastic Packaging Products Limited, Montreal, Quebec, Canada

Filed Mar. 29, 1962, Ser. No. 69,480

Claims priority, application Canada Mar. 3, 1962

Term of patent 14 years

(Cl. D58—13)

The figure is a top perspective view of a compartmented tray, showing my new design.

The characteristic features of my design reside in the combination on the packaging tray shown of low smooth sidewalls which merge with the several transverse partitions, said partitions having smooth top edges, curving at their sides downwardly to said sidewalls, all as shown.

I claim:

The ornamental design for a compartmented packaging tray, as shown and described.
